(57) **CLAIM**

The ornamental design for a graphical user interface for a display screen, as shown and described.

DESCRIPTION

FIG. 1 is a front view of a graphical user interface for a display screen.

FIG. 2 is a front view of a graphical user interface for a display screen, but without the display screen shown in broken line for ease of illustration; and,

FIG. 3 is a front view of a graphical user interface for a display screen shown without broken lines for ease of illustration.

The broken line showing of a display screen in FIG. 1 is included for the purpose of illustrating environmental structure and forms no part of the claimed design. The broken line showing of portions of the graphical user interface for a display screen form no part of the claimed design.

1 Claim, 3 Drawing Sheets

FIG. 1

FIG. 2

FIG. 3
